COMBINED TIMER AND CONDIMENT HOLDERS FOR COOKING RANGE

Jack B. Stuman, Rockford, Ill., assignor to Geo.
D. Roper Corporation, Rockford, Ill., a corporation of Illinois

Application November 8, 1946, Serial No. 134,604

Term of patent 3½ years

(Cl. D81—25)

To all whom it may concern:

Be it known that I, Jack B. Stuman, a citizen of the United States, residing at Rockford, in the county of Winnebago and State of Illinois, have invented a new, original, and ornamental Design for a Combined Timer and Condiment Holders for Cooking Range, of which the following is a specification, reference being had to the accompanying drawing, forming part thereof.

In the drawing:

The dominant feature of the design resides in the portions shown in full lines.

I claim:

The ornamental design for a combined timer and condiment holders for cooking range, substantially as shown and described.

JACK B. STUMAN.
